CLAIM

The ornamental design for a footwear article, as shown and described.

DESCRIPTION

FIG. 1 is a right side view of a footwear article according to the claimed design.

FIG. 2 is a left side view of the footwear article.

FIG. 3 is a front view of the footwear article.

FIG. 4 is a rear view of the footwear article.

FIG. 5 is a top view of the footwear article; and,

FIG. 6 is a bottom view of the footwear article.

The broken lines in the drawings illustrate portions of the footwear article that form no part of the claimed design.
